GEORGE A. JAMES, OF SAN FRANCISCO, CALIFORNIA.

THERMOSTATIC DEVICE.

1,253,041.

Specification of Letters Patent. Patented Jan. 8, 1918.

Application filed February 16, 1914, Serial No. 819,079. Renewed June 16, 1917. Serial No. 175,214.

To all whom it may concern:

Be it known that I, GEORGE A. JAMES, a citizen of the United States, residing at San Francisco, in the county of San Francisco and State of California, have invented new and useful Improvements in Thermostatic Devices, of which the following is a specification.

The object of the present invention is to provide a thermostatic device which may be included in an electric circuit closed by the action of heat or cold upon the device, and which will not be closed by a shock or jar tending to cause vibration of the device.

In the accompanying drawing, Figure 1 is a front elevation of my improved thermostatic device; Fig. 2 is a vertical section on the line 2—2 of Fig. 1, an electric circuit being omitted; Fig. 3 is a vertical section on the line 3—3 of Fig. 2; Fig. 4 is a cross section on the line 4—4 of Fig. 1.

Referring to the drawing, 1 indicates a suitable insulating box or casing having closed sides, back and top, and an open front. The bottom 2 of the casing extends only through the rear half of the depth of the casing, and the lower ends of the sides are enlarged or thickened inwardly to form supports 3, to which are bolted by bolts 4, the lower ends of the brass strips 6 of two pairs of thermostatic members 7, 7', 8, 8'. To these strips are riveted, as shown at 9, vulcanite strips 11. By reason of the different expansion by heat of the brass and vulcanite strips, said thermostatic members bend with each change of temperature. The portions of the strips which are riveted together are of the same length and thickness for the front and back thermostatic members, and consequently the bending effect on them is the same when subjected to the same temperature. The rear thermostatic members, however, are protected from a change in temperature of the surrounding atmosphere or objects by means of a partition 12 slideable in grooves 13 in the inner faces of the enlargements 3 in the sides of the box, and close to the front faces of the bottom 2, said partition extending to substantially the same height as the connected parts of the respective strips. This partition forms with the sides, back and bottom of the box a chamber open only at the top and containing the rear thermostatic members 7', 8', so that the air around said rear members can circulate very slowly and the temperature of said rear

members is not changed, with a change in temperature of objects, or of the atmosphere, in proximity to the box, so quickly as the front thermostatic members, which are exposed to the heat radiated from said objects or to convection of heat by the atmosphere. Said device therefore may be utilized to indicate a rapid change of temperature of surrounding objects or of the atmosphere, for the front thermostatic members respond immediately to said rapid change, whereas the rear thermostatic members do not respond so rapidly thereto. To enable this indication to be made there extend rearwardly from the upper portions of the brass strips of the front thermostatic members arms 14 having on their outer sides cut-away portions 16 across the ends of each of which extends a horizontal platinum wire 17, adapted to contact with a vertical platinum wire 18 extending across the ends of a cut-away portion 19 in the upper end of the brass strip of the corresponding rear thermostatic member. The rear thermostatic members are connected electrically by means of a bent spring plate 20, interposed between, and in contact with, the bolts which attach the lower ends of the brass strips of said members to the box, and the bolts which attach to the box the lower portions of the brass strips of the front members are connected to an electric circuit 21 through a battery 22 and electro-magnet 23.

The four thermostatic members having equal deviations with a given change of temperature, and the rear thermostatic members being better protected than the front members from sudden changes of temperature, it results that, when a sufficient sudden change of temperature occurs, the front members both bend until the platinum wires 17 carried thereby make contact with the platinum wires 18 carried by the rear members, and the circuit is closed. After a length of time depending upon the extent to which the rear members are protected from changes in temperature, that is, upon the height to which the partition extends between the front and rear members, the rear members will become of the same temperature as the front members, and the circuit will again be open.

This difference in the rapidity with which the thermostatic members can respond to changes in temperature of the surrounding atmosphere may be obtained in other ways.

In order that a thermostatic device of this character may be as sensitive as possible, the platinum wires of the respective members of each pair should be at a small distance from, but out of contact with, one another. Consequently they are liable to be brought into contact by a shock or jar which will cause the members to vibrate, thus closing the circuit and causing a false alarm, or other result which is not caused by a change in temperature. It is for this reason that I employ two pairs of thermostatic members instead of one, and I also secure upon the brass strips of the members of one pair weights 26 of brass or other heavy metal, since the period of vibration of a vibratable object varies with its mass, and by securing heavy weights to one pair I cause their vibration period to differ considerably from that of the other pair. Since the vibration periods of the two pairs differ, the members of said pair are never simultaneously in contact with each other, and consequently there is no closure of the elec-

trical circuit, for I thus avoid false alarms, 25 or other results due to the vibrations caused by a jar, and am therefore able to render the instrument more sensitive.

I by no means, however, limit my invention to the precise means here employed for 30 rendering unequal the vibration periods of the two pairs of members.

I claim:—

An apparatus comprising an electric circuit, pairs of vibratable thermostatic members in series therein, the members of each pair being adapted to contact with each other when vibrated, the vibration period of a member of one pair being different from that of a member of the other pair. 35 40

In testimony whereof I have hereunto set my hand in the presence of two subscribing witnesses.

GEORGE A. JAMES.
